SEPARABLE CUFF LINK

Arthur J. Schwartz, New York, N. Y.

Application November 28, 1947, Serial No. 788,463

5 Claims. (Cl. 24—110)

1

The present invention relates to an article of jewelry, and more particularly to improvements in separable cuff-links.

One object of the present invention is to provide a cuff-link of the type indicated having its parts adapted to be easily and conveniently connected and disconnected by the manual operation of means on one of its heads.

Another object is to provide a cuff-link of the type indicated having mechanical coupling means and operating means therefor housed entirely within the cuff-link assembly.

Another object is to provide a cuff-link of the type indicated having resilient means on one of its parts to initiate separation of the two link parts upon disengagement of the coupling means.

Another object is to provide a cuff-link of the type indicated of pleasing and ornamental appearance and of simple and compact construction to adapt it for economical manufacture.

Further objects of the invention are set forth in the following specification which describes a preferred form of construction of the device, by way of example, as illustrated by the accompanying drawing. In the drawing:

Fig. 1 is a side view of a two-part separable cuff-link incorporating the novel features of the present invention;

Fig. 2 is a longitudinal sectional view of the assembled cuff-link taken in a plane common to its longitudinal axis;

Fig. 3 is a sectional view similar to Fig. 2 showing the coupling means as in disconnected relationship to enable separation of the two parts of the cuff-link;

Fig. 4 is a view of the two parts of the cuff-link shown in separated relationship;

Fig. 5 is a transverse sectional view of the cuff-link taken on line 5—5 of Fig. 1;

Fig. 6 is a part-sectional view of the same taken on line 6—6 of Fig. 5 showing the plunger mechanism for actuating the coupling means; and

Fig. 7 is a combination view of the two parts of the cuff-link showing the ends of its post-parts that are adapted for connection by the coupling means.

Cuff-links of the so-called "separable" type usually comprise opposite end heads of ornamental design and a two-part post or shank provided with coupling means for connecting the parts to hold the sides of the cuff joined. In the majority of prior structures of this character ball-and-socket type fasteners are employed for detachably connecting the two link parts.

2

The present improved cuff-link differs from these prior devices in that one link part carries a pilot-member and a retractable latch-element while the other part is formed to telescopically receive and house both the pilot-member and the latching means for coupling the parts together. The formation of the joint thus provided is preferably non-circular whereby rotation of the two link parts is prevented. The latching means is arranged to be actuated by a single plunger slidable longitudinally within one of the heads and normally forced outwardly by resilient means. To prevent unwarranted uncoupling and accidental separation of the two link parts lost-motion is provided between the plunger and the latching means whereby release of the latching means due to accidental pressure applied to the plunger is prevented until the plunger has been depressed to a considerable extent.

Referring more particularly to the accompanying drawing, the cuff-link of the present invention comprises, in general, a two-part separable post 10 at the opposite ends of which are secured appropriate bar-like or elongated cuff-engaging heads 11 and 12 which may be parallel and lie in the same general plane as shown; or at right-angles to each other, or otherwise as desired. As shown in Figs. 1 and 5 the heads 11 and 12 are of tubular form with relatively thin-walls and of circular cross-section, but their configuration may be varied as desired.

The opposite ends of one head 11 are herein shown as closed by cylindrical plugs 13 which may be soldered or otherwise secured in place by any suitable means. The head 12 has one end closed by a fixed cylindrical plug 14 while a plunger 15 projects from its opposite end with a free fit in its bore so as to be capable of sliding movement axially thereof. The plunger 15 and a helical spring 16 positioned between the end of the plunger 15 and the end of the fixed plug 14 constitute the operating means for the latching mechanism to be hereinafter described. The heads 11 and 12 may be fluted or decorated in any other desired fashion, as by engraving, embossing or similar ornamentation.

In accordance with the present invention the cuff-link has its shank or post 10 formed of two hollow parts 18 and 19, preferably tubular in form and adapted for connection in axially-aligned relationship. The heads 11 and 12 are rigidly secured respectively to the outer ends of the parts 18 and 19 of the post 10 and at the inner ends of the parts carry enlarged annular cuff-engaging flanges 20 and 21. The flanges

20 and 21 may be secured to the tubular parts 18 and 19 by soldering or in any other suitable manner and their end faces are adapted to abut at the parting line of the post 10. The flanges 20 and 21 are of substantially concavo-convex form or dished, as indicated at 22 in Fig. 3, and the end portion of the tubular post part 18 is provided with two diametrically-opposed longitudinal slots 23, see Figs. 2 and 4. As shown in Fig. 7, the bore 24 of the post part 18 is non-circular in shape; for example, as herein illustrated it is of square cross-section and has two transversely-opposed tapered grooves 25 extending axially inward of its flanged end in alignment with the slots 23.

Associated with the post part 19 and the head 12 is the novel latching means of the present invention for detachably coupling the two separable link parts to securely connect them together end-to-end in their assembled relationship as illustrated in Figs. 1 and 2. The latching means may comprise a latch-lever 26 pivotally mounted intermediate its ends on a pin 27 extending transversely of the post part 19.

A pilot-member 30 of square cross-section mounted coaxially within the tubular post part 19 is slotted longitudinally in bifurcated form to adapt it to receive the latch-lever 26 between its sides 28, see Fig. 5. The outer end of the pilot-member 30 projects beyond the end of the tubular post part 19 and its associated flange 21 to an appreciable extent to adapt it to be inserted into the bore 24 of the part 18. The latch-lever 26 has a projection or detent-prong 31 at the end of its forward arm 32 for engagement with the end of either one of the slots 23 in the post part 18. The actuating arm 33 of the latch-lever 26 passes through a suitable opening in the wall of the head 12 and engages within a tapered slot 34 extending transversely through the plunger 15 in the head 12. The shape and length of the slot is such as to permit lost-motion between the plunger 15 and lever 26 for a purpose later explained. The arm 33 also serves as a stop to limit outward movement of the plunger 15 under the tension of its spring 16 as shown in Fig. 4.

With the parts in assembled relation as shown in Fig. 2, the prong 31 at the free end of the latch-lever 26 engages through either of the slots 23 in the post part 18 and is securely held in engagement with the detent end of the slot against inadvertent unlatching by the pressure of the spring 16 applied to the plunger 15. A plunger-disk 35 is slidable in the post part 18 and adapted to press against the end of the pilot-member 30 under the tension of a helical spring 36 when the parts of the cuff-link are in connected relationship. The spring 36 is held in place by a pin 37 passing through its coils adjacent one end thereof while its opposite end passes through a suitable opening in the side of the head 11 and is coiled around the reduced shank of the plunger 35. The spring-pressed plunger 35 has as its function to press against the end of the pilot-member 30 to initiate the separation of the two parts of the cuff-link when the latch-lever 26 is released.

The present improved cuff-link is applied to use by inserting the flanges 20 and 21 at the ends of the post parts 18 and 19 through the button-holes at the sides of the cuff and then connecting its parts by forcing the pilot-member 30 into the bore 24 of the post part 18 against the pressure of the plunger 35 activated by the spring 36. The beveled end of the prong 31 on the latch-lever 26 will slide through one of the tapered grooves 25

and cause the end of the lever to be depressed until the prong passes the end of the slot 23, whereafter the lever will be actuated by the spring 16 acting through the plunger 15 to engage the prong 31 with the detent end of the slot 23. The two parts of the link will then be securely connected to hold the sides of the cuff together.

When it is desired to uncouple the parts of the cuff-link it is only necessary to press the plunger 15 inwardly of the head 12 to a sufficient extent to cause it to rock the latch-lever 26 and release its prong 31 from the detent end of the slot 23 as shown in Fig. 3. With the latch-lever 30 thus released the spring 36 will act through the plunger 35 to force the pilot-member 30 endwise and initiate the separation of the two link parts. It will be understood that due to the provision of lost-motion between the plunger 15 and the latch-lever 26 any slight movement of the plunger due to accident will not be sufficient to unlatch the parts of the cuff-link.

It will be observed from the foregoing description that the present invention provides an improved form of cuff-link comprising two separable parts adapted to be coupled together by sliding a pilot-member endwise into an end opening in the other part. It will be observed also that the two parts of the link may be uncoupled and separated easily and conveniently by the simple expedient of pressing the finger against the plunger on one of the heads. Further, the present invention provides a cuff-link of pleasing and ornamental appearance and of simple and compact construction to adapt it for economical manufacture.

While a preferred embodiment of the invention is illustrated and described herein, it is to be understood that modifications may be made in the form and construction of its parts without departing from the spirit or scope of the invention. Therefore, without limiting myself in this respect, I claim:

1. A separable cuff-link comprising a two-part post of tubular form with tubular heads fixed to the outer ends of said post parts in substantially right-angular relation thereto, flanges on the abutting ends of said post parts, a pilot-member held in one post part and projecting therefrom for engagement within the bore of the opposite post part, a latching lever having means adjacent the projecting portion of the pilot-member for engagement with detent-means within the bore of the opposite post part, resilient means for actuating said latching lever to engage it with said detent-means, and means slidable longitudinally in one of the tubular heads for rocking said lever to release it from the detent-means to effect separation of the parts of the cuff-link.

2. A separable cuff-link comprising a hollow post constituted by two parts adapted to be coupled together in axially-aligned relationship, tubular heads at the outer ends of said post parts projecting at substantially right-angles thereto, means projecting from the end of one post part for insertion into the opposite post part, latching means for holding said post parts in connected relationship, means slidable longitudinally on one of the tubular heads for actuating said latching means, and resiliently-operated means in one post part engageable with the end of the projection on the other post part for forcing the two parts of the cuff-link apart when the latching means is released.

3. A separable cuff-link comprising a two-part hollow post with a tubular head at the outer end of one post part extending at substantially right-angles thereto, a pilot-member projecting from the end of one post part for insertion into the end of the opposite post part, a rockable latching lever on one post part engageable with detent-means in the opposite post part for coupling the parts of the post in connected relationship, a plunger slidably longitudinally in said tubular head for rocking the latching lever to release it from said detent-means, a spring for opposing the sliding movement of said plunger, a plunger slidably in one of the post parts for engagement with the end of the pilot-member, and a spring acting on said plunger to force the pilot-member out of the post part with which it interengages when the latching lever is released to initiate separation of the two parts of the cuff-link.

4. A separable cuff-link comprising a two-part tubular post with tubular heads fast on the outer ends thereof, plugs for closing both ends of one of said heads and one of the ends of the opposite head, a plunger slidable in the opposite end of said last-named head, a spring between the end of the plunger and the plug closing the end of the head for resisting slidable movement of said plunger, a latch-lever on one of the post parts with one end extending through an opening in the plunger, said lever having means at its opposite end for engaging detent-means within the opposite post part, and pilot-means projecting from one post part for insertion into the opposite post part to maintain said parts in axial alignment.

5. A separable cuff-link comprising a two-part

tubular post of non-circular cross-section, ornamental heads of tubular construction fastened to the outer ends of the post parts in substantially perpendicular relation thereto, a non-circular pilot member projecting from the end of one post part for insertion into the non-circular interior of the opposite post part for maintaining said post parts in aligned relationship and held against relative rotation, latching means carried by said pilot-member for engagement with detent-means in the post part in which it is inserted, resilient means for normally maintaining said latching means engaged with said detent-means, and a plunger in one of the tubular heads slidably longitudinally against the tension of said resilient means for actuating the latching means to release it from the detent-means to permit separation of the two parts of the cuff-link.
